UNITED STATES PATENT OFFICE.

WALTER J. MADDRELL, OF MINNEAPOLIS, MINNESOTA.

HEAT-GENERATING APPARATUS.

Application filed January 3, 1925. Serial No. 346.

This invention relates to certain improvements in heat generating apparatus; and the nature and objects of the invention will be readily recognized and understood by those skilled in the art to which it relates in the light of the following explanation and detailed description of the accompanying drawings illustrating what I at present consider to be the preferred embodiments or mechanical expressions of the invention from among various other forms, arrangements, combinations and constructions of which the invention is capable within the spirit and scope thereof.

15 The invention is particularly directed to heat generating apparatus of the oil burning type adapted for application to and use in conjunction with the furnaces, boilers and the like of conventional or other heating plants and apparatus, as a substitute for and to take the place of the usual solid or other fuel fires maintained therein for supplying heat thereto; and one of the main and fundamental objects of the present invention is to provide such heat generating apparatus in which a high degree of efficiency in operation is attained through the generation of a maximum amount of heat from a minimum quantity of fuel and with 30 relatively small loss of heat generated from the apparatus.

35 A further object of the invention is to provide heat generating apparatus of the oil burning type which is of simple efficient arrangement and construction and is positive in operation with minimum possibility of failure through stoppage of fuel flow.

40 Another object of the invention is to provide oil burning heat generating apparatus in which the dangers attendant a failure in the proper operation and flow of the oil from the source of supply to the point of combustion are reduced to a minimum and substantially eliminated.

45 A further object of the invention is to provide heat generating apparatus of the oil burning type in which steam is generated and utilized in the vaporization of the oil for combustion.

50 A still further object of the invention is to provide oil burning heat generating apparatus in which steam is generated and employed in vaporizing the fuel for combustion, with means for utilizing the steam to increase combustion and correspondingly

increase or augment the amount of heat generated by the apparatus.

A further feature and characteristic of the invention resides in the provision of a novel method of combustion and heat generation in heat generating apparatus of the oil burning type.

With the foregoing general objects, and certain other objects and results in view, which other objects and results will be readily apparent to those skilled in the art from the following explanation, the invention consists in certain novel features in construction and in combinations and arrangements of elements, as will be more fully and particularly referred to and specified hereinafter.

Referring to the accompanying drawings:

Fig. 1, is a vertical sectional view through the heat generating apparatus embodying the invention, and showing more or less diagrammatically an arrangement of oil supply tanks and supply line therefrom.

Fig. 2, is a detail view in elevation of the oil supply control valve.

Fig. 3, is a view, more or less diagrammatic, in side elevation of heat generating apparatus embodying the invention, as applied to a heating furnace to supply heat thereto.

An embodiment of the invention particularly adapted for use in supplying heat to the furnace of a heating plant or system, as a substitute for the usual fire within the furnace, is disclosed in the accompanying drawings purely by way of example and not of limitation, to permit of explaining the principles and various features of the invention. However, the invention is capable of other embodiments and adapted to other uses and applications, than the embodiment and use presented herewith, as will be readily apparent to those familiar with this art.

The heat generator of the invention, referring now to Fig. 1 of the accompanying drawings in particular, embodies a base portion 1, formed of the spaced inner and outer semi-spherical walls 1^b and 1^a, connected and closed at the lower ends thereof by the ring or annular plate 1^c, to provide the dome-like water reservoir having the water receiving space 1^d. The inner wall 1^b of the base or reservoir 1 is formed with the annular, central vertical extension 1^e pro-

viding a cylindrical passage upwardly through the structure from the space therebeneath, and the outer wall 1^a is formed with the annular vertical extension 1^e, concentric with and spaced from the extension 1^f. An annular plate or ring 1^g is mounted over and connecting the upper ends of the wall extensions 1^f and 1^e to close the upper end of the water reservoir formed by the base 1. Any suitable or desired door or opening (not shown) is provided through the side walls 1^a and 1^b of base 1, to permit of access to the space within and enclosed by the water reservoir forming base, as will be readily understood.

Inner and outer concentric and spaced cylinders 2^a and 2^b are mounted in vertically disposed position on the upper end plate 1^g, of the reservoir base 1, with the lower end of the space between the cylinders closed by the annular plate or ring 2^c. The upper end of the space between the cylinders 2^a and 2^b is closed by a ring or plate 2^d, to provide a closed steam space or chamber 2^e between these cylinders, which form the vertically disposed steam case 2. The space within the inner cylinder 2^a is in communication at the lower end with the space beneath base or reservoir 1, through the vertical cylindrical extension 1^f, and the space in cylinder 2^a forms and provides the combustion space or chamber 3, surrounded and enclosed by the steam chamber 2^e. A steam generating coil 12 is disposed vertically within the combustion chamber 3, and extends upwardly through chamber 3 from the lower end thereof, through which it is in communication with the water space 1^d of reservoir 1 by a bore or opening in plate 1^g, to the upper end of chamber 3, and then downwardly to and discharging into the lower end of the steam chamber 2^e formed between cylinders 2^a and 2^b.

A heat conducting flue or conduit 4 is mounted and fixed at the upper end of the steam case 2 by means of an elbow 4^a with the flue forming an upward and lateral or radial continuation of the combustion chamber 3 of the steam case 2. The elbow 4^a of the flue of conduit 4 is provided with a jacket 4^c therearound closed at the lower end thereof adjacent steam case 2 by a plate or ring 4^d, and forming the superheating steam space 6. The space or chamber 6 formed by jacket 4^c around the elbow 4^a, is placed in communication with the steam chamber 2^e of steam case 2 by the aligned bores 2^f and 4^e formed through upper end plate 2^a of steam case 2, and the lower end closure plate 4^d of jacket 4^c, respectively, as will be clear by reference to Fig. 1 of the accompanying drawings.

The water reservoir or base 1 of the generator is supplied with water from a suitable service tank 10 through a pipe or con-

duit 9 from the tank to and discharging into the water space 1^d of reservoir or base 1. The tank 10 is supplied with water from a service pipe 11 discharging thereinto and controlled by a float operated valve 13 of 70 the usual or any other desired type for maintaining a constant level or supply of water in the tank 10, as will be readily understood. To insure proper functioning of valve 13 to maintain the desired supply 75 or level of water in tank 10, a pressure equalizing pipe extends from the upper end of tank 10, through the steam case 2, and discharges into the steam generating coil 12 within the combustion chamber or space 3. 80

An oil burner 8 is mounted and disposed within the space enclosed by the reservoir forming base 1, beneath the passage through the cylindrical extension 1^f opening into the combustion chamber 3, and is formed 85 with an oil well 8^b therewith having an oil discharge nozzle 8^c extending vertically therefrom beneath and in alignment with the passage through 1^f. The upper side of the burner 8 is formed to provide a shallow 90 oil receptacle 8^d surrounding the oil discharge nozzle 8^c.

Oil is supplied to the well 8^b of the burner 8 from a main supply tank 15 and a service tank 16 mounted therebelow and receiving oil therefrom through the pipe 17 which depends a distance into service tank 16. The level or quantity of oil in service tank 16 is controlled and determined by the depth to which pipe 17 depends into this tank, 100 as when the oil in tank 16 reaches a level closing pipe 17 the air is shut off and the flow of oil from main tank 15 is stopped, and when the level falls and exposes the end of pipe 17 the oil will again flow from tank 15 to raise the level of oil in the service tank to the desired point. An overflow pipe 18 is provided from the service tank 16 to any desired point, to carry off excess oil from tank 16 in the event of 110 failure of the body of oil in tank 16 to cut off the flow through pipe 17, as for example by the entrance of excess air to the main tank 15 and continued flow of oil through pipe 17 after immersion by the body of oil 115 in the service tank. From the service tank 16, the oil is fed by gravity to the oil well 8^b of the oil burner 8 by pipe 19, flow controlling or level maintaining valve 20, and pipe 21 which discharges into the bottom 120 of the oil well through the bore or port 8^c. The flow controlling or level maintaining valve 20 is of any suitable or desired type or construction capable of automatically shutting off the flow of oil to the burner when the level thereof in oil well 8^b reaches a predetermined point, and of permitting flow of oil to such well when the level falls below the desired predetermined point. Such types of valve are well 125

known in the art.

known and understood and any of the conventional types familiar in the art may be employed or other types capable of securing the desired results.

5 A steam chamber 8^a is formed in the burner 8 beneath the oil well 8^b and is provided with a discharge nozzle 8^d extending vertically through the well and discharging therewith above the maintained 10 level of oil in the well, this nozzle 8^d being below and vertically aligned with the oil discharge nozzle 8^e so as to discharge therethrough. A superheated steam pipe 7 extends from the steam chamber 8^a of burner 8, upwardly through the combustion chamber 3, to the superheating steam chamber 6 with which it is in communication and from which it receives superheated steam through the bore or port 4^f . A needle valve 22 is 15 mounted in the steam jacket 4^e to control the steam admitted to pipe 7 through the port 4^f , and is accessible on the exterior of the jacket 4^e for adjustment. Thus, 20 superheated steam is discharged from chamber 6, the quantity being controlled by needle valve 22, through pipe 7, chamber 8^a , and nozzle 8^d , and then through oil well 8^b and nozzle 8^e into the combustion chamber 3 within the steam case 2.

25 Within the elbow 4^a of the heat conducting flue or conduit 4, a series of iron points or fingers 4^b are mounted depending from the upper wall thereof above the combustion chamber 3 of the steam case 2, for a purpose appearing and explained hereinafter. These iron fingers or points 4^b are preferably so mounted as to be replaceable or renewable if desired or as found expedient.

30 In operation of the heat generating apparatus above described as carrying out the method of combustion and heat generation of the present invention, the oil supply tanks 15 and 16 are rendered operative to supply oil to the oil well 8^b of burner 8, the level of which is automatically maintained by valve 20, and the water supply tank 10 is operated to maintain the water supply in the space 1^d of the reservoir forming dome or base 1 of the apparatus. To 35 start the combustion of fuel and heat generation, the shallow receptacle 8^c on the top of the burner is filled with oil and ignited, and the heat generated thereby passes through the chamber 3 and around the steam coil 12 therein with the resulting generation of steam which passes therethrough into steam chamber 2^e , superheating chamber 6, pipe 7, steam chamber 8^a of burner 8, and then through the oil well 8^b where it aids and assists in the vaporization of oil therein and discharges with the vaporized oil through nozzle 8^e , where the oil is ignited and burns. The heat generated by the burning of the oil discharged from 40 the burner 8 passes upwardly through chamber

3 70 burner 3, generating steam in coil 12, and outwardly through elbow 4^a and flue 4 to the point of consumption and use, superheating the steam in chamber 6 of elbow 4^a as it passes therethrough. Once the oil is vaporized and ignited by the priming or starting charge in receptacle 8^c of the burner and steam is generated in coil 12, the operation becomes continuous and automatic until stopped by shutting off the supply of oil 75 to the burner. The steam chamber 8^a of the burner beneath the body of oil in the oil well 8^b heats the oil and assists in the vaporization thereof and discharge from the well by the steam from the nozzle 8^d . Efficient combustion of the oil is secured by the vaporization and discharge through the action of the steam projected under pressure upwardly through the well above the surface of the oil therein.

80 Another feature of the invention provides an added step in the process of combustion to increase and augment the heat generated, by utilizing the hydrogen from the steam injected into the chamber 3 from 85 the burner. The heat generated by the combustion of the oil passes through elbow 4^a and heats the iron fingers 4^b to incandescence or a dull or cherry red heat, with the result that as the steam from the nozzle 8^e 90 of burner 8 comes into contact with this incandescent or heated iron, the hydrogen in the steam is liberated and ignited with the resulting increase in combustion and heat generated and delivered to flue 4 by the apparatus.

95 In Fig. 3 of the accompanying drawings, a possible application and use of the embodiment of the invention presented herewith is disclosed. A conventional or other furnace, boiler or the like 5, of a heating plant or system is shown as including the usual fire door or the like 5^a by which access is had to the fire box or combustion chamber thereof in which a fire is maintained to supply the desired heat. With the apparatus 100 of the invention, the heat flue or conduit 4 is mounted discharging through the fire door opening into the furnace 5 to supply heat thereto in place of the usual fire. The 105 heat generating apparatus with the oil and water supply tanks and lines is mounted at any convenient or desired point, such for example as the disposition more or less diagrammatically indicated by Fig. 3, and the 110 operation thereof and method of combustion and heat generation is carried out in the manner hereinbefore described.

115 With the invention involving the apparatus and method of combustion as set forth 120 efficient operation and resulting heat generation is secured. The apparatus is safeguarded by the automatically controlled fuel and water supply and due to the simplicity of the apparatus positive operation is 125 130

obtained with a minimum possibility of failure in operation. The invention is not restricted to the embodiment of the apparatus 5 adapted to various other uses and embodiments where the generation of heat may be desired.

It is also evident that various changes, modifications, substitutions and variations 10 might be resorted to without departing from the spirit and scope of my invention, and hence I do not desire to limit myself to the exact and specific disclosures hereof.

Desiring to protect my invention in the 15 broadest manner legally possible, what I claim and desire to secure by Letters Patent of the United States, is:

1. In heat generating apparatus, an oil burner, means for supplying oil thereto, a 20 water reservoir, a steam chamber, a steam generating coil extending from said reservoir to said chamber and heated by said burner, and a steam line from said chamber to the burner to vaporize the oil in the 25 burner for combustion thereby.

2. In heat generating apparatus, an oil burner, means for supplying oil thereto, a water reservoir, a steam drying chamber, a steam superheating chamber in communication with the drying chamber, a steam generating coil heated by said burner extending from the reservoir to and discharging into said drying chamber, and a steam line from said superheating chamber to the 30 burner for vaporizing oil therein for combustion thereby.

3. In heat generating apparatus, an oil burner, oil supply means therefor, a water reservoir surrounding said burner, a combustion chamber above said burner and reservoir open to the burner through the reservoir, a steam chamber surrounding said combustion chamber, a heat conduit for conducting heat from said combustion chamber, a 40 steam coil extending through said combustion chamber from the reservoir to the steam chamber, and a steam line from the steam chamber to said burner for supplying steam to vaporize the oil for combustion by the 45 burner.

4. In heat generating apparatus, an oil burner, means for supplying oil thereto, a water reservoir, a combustion chamber for said burner, a steam chamber surrounding 50 the combustion chamber and in communication with said reservoir, and means for supplying steam from said steam chamber to and projecting steam through said burner to vaporize the oil therein for combustion 55 thereby, the steam being discharged by the burner into said combustion chamber.

5. In heat generating apparatus, an oil burner, means for supplying oil thereto, a combustion chamber for said burner, a conduit from said chamber, means for generat-

ing and projecting steam through said burner to vaporize the oil for combustion thereby, said burner projecting the steam into said chamber, and means for liberating hydrogen from the steam in said chamber 70 for ignition and combustion therein.

6. In heat generating apparatus, an oil burner, means for supplying oil thereto, a combustion chamber for said burner, means for generating and projecting steam through 75 said burner to vaporize the oil therein for combustion thereby, said burner discharging the steam into said chamber, and means embodying a series of iron elements in said chamber heated therein for contact by the 80 steam and liberation and combustion of the hydrogen from the steam.

7. In a method of combustion and heat generation, those steps which consist in igniting and burning fuel oil, generating 85 steam by the combustion of the oil, heating the oil to vaporize the same for combustion by the generated steam, projecting steam upwardly through and above the steam heated oil to draw the vaporized oil therefrom for combustion, heating iron by the combustion of the oil, bringing the projected steam in contact with the heated iron to liberate the hydrogen, and then igniting and burning the hydrogen so liberated. 95

8. In heat generating apparatus, an oil burner, a water reservoir surrounding said burner, a combustion chamber above said burner and reservoir to receive the heat from the burner, a steam generating chamber surrounding the combustion chamber, a steam coil extending through the combustion chamber from the reservoir to the steam chamber, and a steam line from the steam chamber extending through the combustion chamber 100 to said burner for supplying steam thereto. 105

9. In heat generating apparatus, an oil burner, a water reservoir surrounding said burner, a combustion chamber above said burner, a steam chamber surrounding the combustion chamber, a steam coil extending from the upper part of the reservoir upwardly through the combustion chamber and downwardly to the lower end of the 110 steam chamber, and a steam line extending through the combustion chamber from the steam chamber to said burner. 115

10. In heat generating apparatus, an oil burner, a water reservoir surrounding said 120 burner, a combustion chamber above the burner, a steam chamber surrounding the combustion chamber and formed with a steam superheating chamber at the upper end thereof, a steam coil extending through 125 the combustion chamber from the reservoir to the steam chamber, and a steam line extending through the combustion chamber from the superheating chamber to said oil burner. 130

11. In heat generating apparatus, an oil burner including a steam chamber for heating the oil, a water reservoir surrounding said burner, a combustion chamber above said burner, a steam chamber surrounding said combustion chamber, a heat conduit extending from and in communication with the combustion chamber, a superheating steam chamber surrounding the inner end 10 of said conduit in communication with the steam chamber, a steam coil extending through the combustion chamber from the steam chamber to the reservoir, and a steam line extending through the combustion 15 chamber from the superheating chamber to the steam chamber of said oil burner.

12. In heat generating apparatus, in combination, an oil burner, a combustion chamber therefor, a steam chamber surrounding the combustion chamber, means for discharging steam into and through the combustion chamber, and iron members disposed in the combustion chamber for heating therein and contact of steam to liberate the 20 hydrogen from the steam.

25

13. In heat generating apparatus, an oil burner, a combustion chamber therefor, a steam chamber surrounding the combustion chamber, means for discharging steam from the steam chamber into and through the 30 combustion chamber, and a series of iron members disposed in the combustion chamber for heating and contact by the steam therein to liberate the hydrogen therefrom for combustion.

35

14. In heat generating apparatus, an oil burner, a combustion chamber therefor, a steam chamber surrounding the combustion chamber, a heat conduit extending from the outer end of the combustion chamber, means 40 for projecting steam into and through the combustion chamber, and a series of iron members within the conduit for heating therein and contact with the steam from the combustion chamber to liberate and burn 45 the hydrogen therefrom.

Signed at Minneapolis, Minnesota, this 8th day of December, 1924.

WALTER J. MADDRELL.
